UNITED STATES PATENT OFFICE

133,045

DESIGN FOR A TOY SAVINGS BANK

Gladys L. Turner, Rock Island, Ill.

Application September 16, 1941, Serial No. 103,375

Term of patent 3½ years

To all whom it may concern:

Be it known that I, Gladys L. Turner, a citizen of the United States, residing at Rock Island, in the county of Rock Island and State of Illinois, have invented a new, original, and ornamental Design for a Toy Savings Bank, of which the following is a specification, reference being had to the accompanying drawing, forming a part thereof.

Fig. 1 is a front elevational view of a toy savings bank, showing my new design;

Fig. 2 is a top plan view thereof; and

Fig. 3 is a side elevational view.

What I claim is:

The ornamental design for a toy savings bank, as shown.

GLADYS L. TURNER.
